ATTORNEY.

UNITED STATES PATENT OFFICE.

JOHN R. REPLEGLO, OF DETROIT, MICHIGAN, ASSIGNOR, BY MESNE ASSIGNMENTS, TO ELECTRIC REFRIGERATION CORPORATION, OF DETROIT, MICHIGAN, A CORPORATION OF MICHIGAN.

REFRIGERATED CABINET.

Application filed April 19, 1926. Serial No. 102,929.

This invention relates to food cabinets, and more particularly to refrigerated cabinets employed for storing food, soft drinks and the like, which are dispensed at a low 5 temperature.

Cabinets of the above character are usually constructed with a flat sheet metal top having openings therein to provide access to interior compartments, and removable lids 10 are arranged to project partially within the openings and to rest upon the top, adjacent the openings, to close the compartments from external warm air. With the flat tops now used for cabinets, food or liquid which 15 is spilled thereon can be readily wiped off, but such things are often wiped or flow into the food compartments. When cans of ice cream or other articles are dropped upon the edge of the sheet metal tops adjacent the 20 openings, their conformation is changed such that the lids will not fit tightly thereagainst and, therefore, warm air will pass into the compartments when the lids are in position to close the compartments.

One of the objects of this invention is to 25 provide a raised beading in the top of a food cabinet adjacent the openings to prevent food and liquids from flowing into or being readily wiped into the food compartments.

Another object of my invention is to provide a sheet metal top for food cabinets which is formed with non-deformable seat 30 portions adjacent the openings which lead 35 to the food compartments, so that a tight closure is always assured when the lids are seated over thereagainst.

A further object of my invention is to 40 provide a top for a cabinet which is formed of a single sheet of metal bent to provide 45 beadings surrounding openings therein so that no cracks or joints are present in which food or liquid can collect and become insanitary.

Other objects of the invention, more or 45 less incidental or ancillary to the foregoing, will appear in the following description, which sets forth in connection with the accompanying drawing a preferred embodiment 50 of the invention.

In the drawings, Figure 1 is a top plan view of a four hole refrigerated food cabinet having one of the lids removed; and

Figure 2 is a fragmentary sectional view 55 taken on line 2—2 of Figure 1, showing the construction of the cabinet medially through two of the food compartments, one of the lids being removed.

Referring now to the drawings by characters of reference, the cabinet illustrated 60 is formed to provide four food compartments and my invention can be applied to any conventional form of refrigerated food cabinet. Superposed top wall members 10 and 11 65 form the upper part of the cabinet structure and are provided with a plurality of circular aligned openings. The lower top wall member 10 is provided with recesses 12 adjacent each opening, into which the circular flange 13 of sheet metal sleeves 14 extend and 70 are supported. The sheet metal sleeves 14 are of substantially the same form and diameter as the openings in the top member 10, and project downwardly into the cabinet, forming food compartments. The upper 75 surface of the top wall member 11 is provided with circular recesses 15, extending exteriorly from the openings therein.

A sheet metal casing top 16, preferably 80 formed of "Monel" metal, is secured to enclose the top member 11 of the frame of the cabinet. The sheet metal top casing is provided with circular openings arranged to align with the 85 openings in the top members 10 and 11, and the edge portions adjacent such openings are bent to form circular raised beadings 17. A hard metal filler ring 18, preferably circular in cross section, is arranged to rest upon the top member 11 and within each of the 90 recesses 15 formed therein. The beadings 17 of the sheet metal casing top are bent around the filler rings 18, so that they tightly engage the same, and are of such length as to extend around the rings a sufficient distance to prevent relative displacement. It will be understood that the filler ring could be formed of hard wood or strong metal tubing, and also that the shape of the openings and the 95 beading need not necessarily be circular.

It will be seen that the raised beadings 100 will prevent any foreign matter, such as ice cream, water, cleaning material and the like, from being readily brushed into the food compartments when the top of the cabinet is wiped off. It will also be seen that the 105 beadings project above the surface of the

sheet metal casing adjacent each of the food compartment openings and with their reinforcement provide a substantially non-deformable seat for the closure lids 19. The 5 filler rings resting on the top wall will receive blows against the beadings, so that the shape of the beadings or seats can not become deformed and allow warm exterior air to pass between the beadings and the lids, 10 when the lids rest thereagainst to close the open ends of the food compartments. It will also be seen that the top is formed of a single sheet of material and that there are no joints or cracks in which liquids, food, 15 and the like, can collect to cause an insanitary condition.

While I have shown and described in detail a preferred form of construction, it will be understood that there can be wide varia-

tion from such structure, without departing 20 from the spirit of the invention and the scope of the appended claim.

What I claim is:

In a refrigerated food cabinet, a frame 25 having vertically extending compartments therein open at their upper ends, the upper surface of said frame being recessed adjacent said openings, a sheet metal top casing formed with openings therein in alignment with the open ends of said compartments, 30 and substantially non-deformable filler members seated in the recess in said frame beneath said sheet metal top casing, the casing adjacent the openings being bent around said filler members to retain them in position. 35

In testimony whereof, I hereunto affix my signature.

JOHN R. REPLOGLE.
